By John S. Facker
Attorney

UNITED STATES PATENT OFFICE.

GEORGE B. WELSER, JR., OF MILWAUKEE, WISCONSIN, ASSIGNOR TO CHAIN BELT COMPANY, OF MILWAUKEE, WISCONSIN, A CORPORATION OF WISCONSIN.

MECHANISM FOR OPERATING CLEANING BRUSHES AND SIMILAR APPARATUS.

Original application filed March 25, 1919, Serial No. 284,926. Divided and this application filed October 19, 1922, Serial No. 595,586. Renewed June 7, 1927.

The invention presented in this case, which is a division of my application filed March 25, 1919, Serial No. 284,926, which application has matured into Patent No. 5 1,435,770 dated November 14, 1922, relates to mechanism for operating cleaning brushes, such as are used to remove the material collected upon the surfaces of liquid screens, as for instance, those employed in 10 the treatment of sewage, or of water taken from a natural stream to be used for industrial purposes. While the invention has been devised with special reference to use in connection with apparatus such as stated, 15 I do not wish to be limited in its useful applications to apparatus such as shown in the drawings, for other devices than brushes might be operated by the mechanism shown, and the brushes or other devices might be 20 used in connection with apparatus other than liquid screens.

In the accompanying drawing, in which I have illustrated the invention applied to a liquid screening apparatus—

25 Figure 1 is a top plan view of an apparatus embodying the invention;

Fig. 2 is a longitudinal sectional view through the brushing apparatus taken on the line II—II of Fig. 1;

30 Fig. 3 is a top plan view of a short section of the brushing apparatus;

Fig. 4 is a longitudinal sectional view of a portion of the apparatus;

35 Fig. 5 is a transverse sectional view on the line V—V of Fig. 4.

In the drawings, 2 indicates a water screen of the endless, traveling type, formed of a series of perforated plates 27 carried by parallel chains that pass about head and 40 foot wheels, supported in a frame 3. As the construction of the screen itself forms no part of the present invention it need not be described in detail. Suffice it to say, that means are provided for causing the screen 45 to be slowly moved through the liquid that is to be cleaned of material such as will be taken therefrom by the perforated plates 27. The liquid flows through a chamber designated 4 into which the screen dips. 50 The upper run of the screen, which is the working portion thereof, moves in the direction of the arrow *a*, Fig. 1, traveling from the submerged foot wheel to the head wheel,

and being, when in use, in an inclined position, as is common in apparatus such as 55 herein represented. The material that collects upon the surface of the screen and is held thereon by the force of gravity is lifted out of the liquid, as the screen plates successively emerge therefrom. After the liquid with which it is saturated, has somewhat drained therefrom it is removed by a series of brushes 5 that are moved so as to 60 sweep across the surfaces of the screen.

So far as the present invention is concerned the direction of travel of the brushes 5 may be at right angles to the direction of movement of the screen 2, or oblique thereto, as indicated in Fig. 1, the latter arrangement being preferred for reasons that are 70 set forth in detail in my aforesaid application of which this case is a division. The brushes 5 are connected with and moved by a pair of parallel chains 6 that run in engagement with wheels 7, 7' supported in a 75 frame 8. This frame is preferably supported by the frame 3 of the water screen and is transverse thereto. The means employed for supporting the brush frame from the screen frame are not illustrated in detail, 80 since they form no part of the present invention. The two frames are preferably connected in order that their working relations may be maintained whatever be the 85 adjustment of the screen frame.

The chains 6 are preferably provided with wheels 9 that run in engagement with tracks 10 suitably supported by the frame 8, this arrangement providing for the steady movement of the chains and the parts they carry 90 during operation of the apparatus. Cross pieces 11 unite the opposite chains and hold them properly spaced apart, and also serve as bearings for certain adjustment bolts 24 that will be presently described. The 95 brushes 5, of which there are several in a machine such as illustrated, although an apparatus with one only would for some purposes be operative, are supported upon shafts 12, which are mounted near their opposite ends in bearings 13 carried by arms or links 14. These in turn are supported upon cross shafts 15 supported in bearings 16 that are mounted in housings or slideways 17 suitably secured to the chains 6, in which the 100 said bearings 16 are free to move to a limit. 105

ited extent. To each shaft 15 is secured a gear wheel 18 that runs in mesh with a stationary gear element supported in the frame 8 and paralleling in a general way the tracks 10 which gear element is preferably in the form of a rack 19. As will be seen by reference to Fig. 2 the tracks 10 are not continued around the wheels 7, 7' at the ends of the frame 8 where the conveyor chains 6 turn, because at these parts of the course of the chains the wheels 7, 7' hold them steady, and the tracks 10 are therefore unnecessary. There is another reason for dispensing with the tracks adjacent to the wheel 7', for this wheel is adjustable, by means of devices such as represented at 20, in order that the chains 6 may be kept taut as they stretch and wear in use. The rack 19 with which engage the wheels 18 is however preferably continued at the ends of the frame 8, so that it may be said to parallel the entire course of the conveyor chain 6 next to which it is supported. A train of gearing 21 is interposed between the shafts 15 and 12; and from the arrangement described it will be seen that as the conveyor chains 6 move in the direction of the arrow in Fig. 4,—carrying with them the slideways 17, and these in turn carrying the shaft 15—the gear wheel 18 will be caused to turn by reason of its engagement with the rack 19, thus rotating the shaft 15, from which rotary motion is transmitted through the train of gearing 21 and shaft 12 to the brush 5. The speed of rotation of the latter will be such as to properly clean the surfaces of the screen, and this speed will be insured by the proper relationship in size between the wheels constituting the gear train 21.

The shafts 15 are extended outward beyond their bearings 16 to afford supports for the wheels 22 that run in engagement with tracks 23, that parallel the rack 19 throughout its entire course. This arrangement insures that the gear wheels 18 shall always be maintained in proper meshing engagement with the rack 19, notwithstanding the bearings for the shafts 15 are movable or floating and may change their positions with reference to the slideways in which they are supported.

A bolt 24 is pivotally connected with the free end of each link or arm 14, its outer end being seated in one of the cross pieces 11, and an expansion spring 25 surrounds each bolt, having bearing at one end against the cross piece 11 and at the other end acting upon the bolt. These springs operate to hold the brushes 5 against the surfaces which they are to clean, with the desired force. Suitably adjusted nuts 26 are upon the bolts 24, by means of which the tension of the springs 25 is controlled.

Driving mechanism is employed to move the screen 2 and also the cleaning mechanism; but it is not deemed necessary here to illustrate such driving means as these may be of any preferred arrangement, and constitute no part of the present invention.

The operation of the apparatus may be easily understood from the foregoing description taken in connection with the accompanying drawings.

The conveyor chains 6 are driven, carrying the tools 5 across the face of the surface to be acted upon, through power applied to one of the wheels 7 or 7'. As the brushes are moved they are caused to rotate, as has been explained, by reason of the engagement of the wheels 18 with the rack 19. As the chains stretch and wear they become loose, making it desirable to adjust the wheel 7' to take up the slack, the position of such wheel after adjustment being indicated by dotted lines in Fig. 2. It will be seen by reference to this view that the distance between a chain 6 and the rack 19, along the straight portions of the course of the chain, is the same as the distance between the chain and the rack at the central portion of its turn around the wheel 7' when such wheel is in the position indicated in full lines, this being the position it will occupy when the chains 6 are new and unworn; but that the distance between the chains and the rack along the said straight portions is greater than the distance between the chain where it makes the turn around the wheel 7', when the latter occupies the dotted line position, that is, after it has been adjusted to take up slack in the chain. But as the distance between the rack 19 and the track 23 is the same throughout the entire course of each it follows that there must be some relative movement of the shafts 15 and the chains as such shafts, and the parts which they carry, pass the wheel 7', and this is provided for by the floating or movable bearings 16 in which the shafts 15 are mounted and the slideways 17 carried by the chains, in which said bearings move. This arrangement insures accurate working of the parts of the apparatus and at the same time permits the supporting wheels for the chains 6 to be adjusted to keep them taut and in best working condition.

Should for any reason it be necessary for the chains 6 and the rack 19 to depart from their parallel relation at points intermediate between the wheels 7 and 7', the construction described would permit this without interfering with the working relations of the parts. Should such a departure take place the track 23 should follow the course of the rack 19 rather than that of the chains 6.

It will be apparent that rotating tools other than a brush might be supported upon the shafts 12, such tools being arranged to operate upon a surface over which they

might be moved. In such an arrangement no change need be made in the mechanism shown and described other than the replacement of the brush by any desired tool.

5 It will be seen that the movements of the bearings 16, relative to the chains 6, are in planes parallel to those in which the chains travel,—that is to say, to planes including the oppositely moving strands of the chains 10 and the wheels 7, 7' with which they engage,—so that as the bearings 16 move in their slideways 17 while passing around the wheels 7 they move on lines radial to the axis of rotation of that wheel.

15 Having thus described my invention what I claim and desire to secure by Letters Patent is:

1. In apparatus such as described, the combination of an endless power chain, supporting wheels with which it engages, a tool connected with the chain and arranged to operate on a surface across which it is thereby moved, a stationary gear element paralleling the course of the power chain, and driving connections for operating the tool, engaging with the said gear element and free to move toward and from the chain, whereby working conditions between the gear element and driving connections are maintained, even 20 though the former and the power chain should cease to be in parallelism.

2. In apparatus such as described, the combination of an endless power chain, supporting wheels with which it engages, one of 25 which is adjustable to take up slack in the chain, a stationary gear element closely paralleling the chain throughout its entire course, a rotating tool connected with the chain and arranged to operate on a surface 30 across which it is thereby moved, and gearing for rotating the tool, one element of which moves in engagement with the stationary gear element and is caused to be driven thereby, such moving element being free to 35 move toward and from the chain in order that working engagement with the stationary gear element may be maintained even though it and the power chain should cease 40 to be in parallelism.

50 3. The combination stated in claim 2 including also supplemental means for maintaining proper engagement between the said gearing and the stationary gear element.

4. In an apparatus such as described, the 55 combination of an endless power chain, supporting wheels with which it engages, one of which is adjustable to take up slack in the chain, a stationary gear element following more or less closely the entire course of the 60 chain, a rotating tool arranged to operate on a surface across which it is to be moved by the said chain, connections between the said tool and the chain including a shaft and bearings in which it is mounted, mov- 65 able relative to the chain, gearing for rotat-

ing the tool, one element of which is on the said shaft and engages with the stationary gear element, by which it is caused to rotate, a guide parallel with the stationary gear element throughout its course, and a part carried by the said shaft running in engagement with the guide and arranged to maintain the gear member in proper working relation with the stationary gear element. 70

5. In a cleaning apparatus, a brush, endless chains that move the brush over the surface to be cleaned, wheels around which the chains pass, means for adjusting at least one of said wheels to take up slack in the chains, a stationary gear element following the course 75 of the chains and passing around the said wheels, gearing moved by the chains, engaging with the said stationary gear element for driving the brush and floating bearings for the gearing that is moved by the chains. 80

6. In a cleaning apparatus, the combination of a brush, endless chains that move the brush across the surface to be cleaned, wheels about which the said chains pass, adjusting means for one set of wheels to take up slack 85 in the chains, a continuous stationary gear element following the entire course of one of the chains and extending around the wheels, gearing movable with the endless chain and operated by engagement with the said stationary gear element for rotating the 90 said brush, and means for causing continuous engagement of the movable gearing with the stationary gear element, including engagement at that end where are located the 95 means for maintaining proper chain tension. 100

7. In a cleaning apparatus, the combination of a rotating tool, endless chains that move the tool, floating bearings interposed between the tool and chains, from which the former is supported, a stationary gear element following the course of one of the chains, gearing supported from the said floating bearings for rotating the brush, one element of which engages said stationary 105 gear element, and guides for the floating bearings arranged to maintain the said gear- 110 ing in proper working engagement with the stationary gear element.

8. In a cleaning apparatus, the combination of a brush for cleaning a surface, endless chains that move the brush, a gear rack following the course of one of the chains, floating bearings from which the brush is supported interposed between the latter and the chains, gearing for driving the brush supported from the said floating bearings, one element of which engages the gear rack, guides for the floating bearings paralleling 120 the gear rack, for maintaining proper engagement of the gearing with the rack, and a spring for holding the brush in proper working engagement against the surface to be cleaned. 125

9. In a cleaning apparatus, the combina- 130

tion of a brush, endless chains for moving the brush over the surface to be cleaned, slideways carried by the chains, floating bearings mounted in the slideways from which the brush is supported, means for holding the brush against the surface being cleaned, and guide tracks for the chains for preventing such movements thereof as might cause disengagement of the floating bearings from the guideways in which they are mounted.

10. In a cleaning apparatus, the combination of a brush, endless chains for moving the brush over a surface to be cleaned, floating bearings carried by the chains, a shaft

20 supported in the bearings, links mounted on the shaft and carrying the brush, a stationary rack following the course of one of the chains, and gearing on the shaft in the floating bearings in mesh with the rack and causing rotation of the brush as it moves over the surface being cleaned, the links permitting a certain freedom of movement of the brush relative to the floating bearings.

25 11. The combination stated in claim 10 including also guides for the shaft carrying the floating bearings, for maintaining the gearing in proper mesh with the rack.

GEORGE B. WELSER, JR.
